UNITED STATES PATENT OFFICE.

PAUL MIRK, OF NEW YORK, N. Y.

THERMOSTATIC VALVE.

1,341,016.

Specification of Letters Patent.

Patented May 25, 1920.

Application filed July 3, 1919. Serial No. 308,550.

To all whom it may concern:

Be it known that I, PAUL MIRK, a subject of Germany, (who has declared his intention to become a citizen of the United States,) and resident of the city of New York, in the county of New York and State of New York, have invented certain new and useful Improvements in Thermostatic Valves, of which the following is a specification.

This invention relates to automatic air-relief valves for steam radiators and analogous structures, having reference particularly to that class of valves in which a thermostatic controlling device is employed.

The object of my invention is to provide a thermo-acting valve of simple, inexpensive and efficient construction which permits the discharge of confined air from the radiator, &c., by the pressure of the advancing steam, and yet effectually precludes the escape of the steam to the atmosphere; the components of which valve are so constructed and organized that the thermostatic member thereof is isolated from the path of the steam and is influenced solely by the thermal condition of the radiator; and that normally the said member acts to maintain the valve open in order to permit the escape of the air, yet when the member is influenced by the heat of conduction from the radiator, &c., the valve head is released and permitted to be positively closed by means extraneous of the thermostatic member, thus preventing the escape of the steam.

A further object of my invention is to provide a valve having a thermostatic device which can be simply and cheaply constructed and readily applied to or removed from the valve structure and which device possesses the further merits of functional reliability and durability.

With these and other objects in view my invention comprises novel features of construction and combinations of parts which will be hereinafter fully described and claimed.

In the annexed drawings—

Figure 1 is a side elevation of a thermostatic air-relief valve embodying a preferred form of my invention.

Fig. 2 is a longitudinal vertical section of the same, enlarged.

Referring to the drawings, 10 designates a metal body having a central bore 11 into

one end of which is screwed a projection 12 having an axial port 13 extending therethrough. This projection may be integral with the body if desired. The opposite end 60 of the body comprises a screw-threaded portion 14' adapted to be entered into a tapped orifice in the wall of a radiator section or other steam-heated metal structure. Within the body is loosely fitted a valve 65 head 14 which is movable toward or from the inner end of the port 13 so as to close or open the latter as desired. A spring 15 confined within the body 10 tends to urge the valve head to closing position, which 70 spring in the present instance bears at its respective ends against the opposing end of the valve head and an internal flange 16 on the lower end of the body.

Extending loosely through the axial port 75 of the projection 12 is a pin 17, one end of which rests upon the movable valve head while the other end projects exteriorly of the projection, whereby the pin may be forced inwardly in order to move the valve head 80 from its closing position in opposition to the action of the spring. Screwed into a tapped socket in the exterior of the body 10 is the extremity of one leg 18 of a U-shaped thermostatic device, the other leg 85 19 whereof is positioned to overhang the outer projecting end of the pin. Normally the leg 19 bears upon the pin 17 in a manner to hold the valve head 14 positively in down or open position against the stress of the 90 spring; but the construction of the thermostatic device is such that when it is subjected to a predetermined temperature the leg 19 is deflected upward or outward sufficiently to permit the spring to press the valve head to 95 its seat. Hence when the radiator, for example, is below a predetermined effective temperature the valve is open, and the air, under the pressure of advancing steam, is permitted to escape through the port 13; 100 but when such temperature is reached the thermostatic device, being heated by conduction, is actuated to release the valve head and thus close the port, thereby preventing the escape of the steam to the atmosphere. When the temperature of the 105 radiator again drops the thermostatic device resumes its normal or contracted condition and thus effects the opening of the valve port as before.

The preferred form of thermostatic device herein illustrated comprises a hollow

tubular member closed at its respective ends and filled with a heavy expansible liquid, 20, having a high melting point, such, for example, as linseed or paraffin oil. This member is bent into U-form and secured at one end to the body 10 as above mentioned. Preferably the tubular member is constituted by a cylindrical rod which is longitudinally bored throughout the greater part of its length, the closed end thereof being externally screw-threaded, as at 21, for application to the threaded socket in the body 10. The opposite end of the rod is provided with an internal seat 22 for a fiber plug or gasket 23, and is screw-threaded, as at 24, to receive one end of a solid terminal piece 25. Before the application of the plug and end piece the bored rod is bent into U-form, its hollow body assuming an elliptical form in cross-section, and the bore is filled with the thermal liquid which is introduced through the central aperture in the seat 22. Thus when the plug and end piece are applied the filled member is hermetically sealed. If desired the terminal piece may be soldered as well as screwed to the filled member; the plug or gasket preventing the contact of the thermal fluid with the solder.

The thermostatic device thus constructed can be readily turned on its screw connection and swung laterally of the pin in order to permit the removal, inspection, repair or renewal of the latter or of the internal members of the valve structure.

From the foregoing it will be seen that the metal body of the thermostatic device is isolated from the path of the steam in the radiator, and that said body is heated by conduction, the heat being thence transmitted to the confined thermal liquid in order to expand the latter and thus effect the outward movement of the terminal or bearing end of the device. Hence the operation of the device to permit the closing of the valve by the force of the spring (to which the pressure of the steam contributes) is insured when and only when the radiator or other structure to which it is applied reaches a certain temperature. Since the valve is positively seated as just described, a

reliable sealing of the discharge opening is insured, thus effectually preventing the escape of the steam. Moreover as the device is isolated from the steam as above mentioned, no inclosure for such device is required, and therefore there is no resulting trap for water of condensation.

In some cases the spring may be omitted, in which event the valve head will be forced to its seat by the action of the steam only. 60

It is to be understood that I do not limit my invention to the exact details of construction herein disclosed, as the same may be modified within the principle of my invention and the scope of the appended 65 claims.

I claim—

1. An air valve comprising a body having a port, a radiator-engaging portion, and a screw-threaded thermostatic supporting portion, said latter portion being in angular relation to the longitudinal axis of said body, a valve head confined within said body and arranged to open and close the inner end of the port, a pin extending through said port from the valve head, and a thermostatic device exteriorly of said body and isolated from the steam, said device comprising a U-tube containing a thermal liquid, one end of the tube being closed and having a screw-threaded portion for engagement with the said supporting portion of the valve body, and the opposite end of said tube having a terminal piece which bears against the outer end of the pin and maintains the valve head 85 normally in open condition. 75

2. An air valve having a U-shaped thermostatic device comprising a tubular member closed and externally screw-threaded at one end, and provided with an internal perforated seat at the opposite open end, a gasket arranged within said open end and bearing on said seat, and a terminal piece fitted into said open end and bearing against the gasket. 90 95

Signed at New York, in the county and State of New York, this second day of July, A. D. 1919.

PAUL MIRK.
